UNITED STATES PATENT OFFICE.

JOHN ERICKSON, OF CHICAGO, ILLINOIS, ASSIGNOR, BY MESNE ASSIGNMENTS, TO FIRST TRUST AND SAVINGS BANK, TRUSTEE, OF CHICAGO, ILLINOIS.

AUTOMATIC TELEPHONE-RELEASE.

1,183,832.

Specification of Letters Patent.

Patented May 16, 1916.

Application filed January 22, 1907. Serial No. 353,555.

To all whom it may concern:

Be it known that I, JOHN ERICKSON, a citizen of the United States of America, and resident of Chicago, Cook county, Illinois, have invented a certain new and useful Improvement in Automatic Telephone Releases, of which the following is a specification.

My invention relates to telephone exchange systems in general, but more particularly to automatic or semi-automatic systems, and especially to telephone exchange systems in which automatic selectors or other trunking switches are employed. In systems of this character it has been proposed to automatically cut off the line relay bridges of the selectors or other switches, so as to leave only the bridge or bridges of the connector or final connecting switch across the talking circuit during conversation, and to then employ third conductors or special trunks for releasing the selectors or other similar switches after the two subscribers are through talking. This, of course, leaves the talking circuit comparatively free from bridges across the talking circuit during conversation between the two subscribers, but at the same time necessitates the use of trunk lines each comprising three parallel conductors, the third or special trunk conductor being used for releasing purposes.

The principal object of my invention is, therefore, the provision of an arrangement by which the relay bridges of the selectors and other switches—except the connectors, of course—may be automatically cut off or opened up during the use of any temporarily established talking circuit between two subscribers, and whereby the automatic switches having relays thus temporarily disconnected from the talking circuit may be released without the use of third conductors in the trunk lines. In this way, I obtain the advantages which arise from cutting off or opening up the bridges on any established talking circuit, and at the same time I obviate the necessity of employing third conductors in the trunk lines between the switches, thus effecting a saving in copper or any other material from which the trunk lines are made. As herein described and illustrated, I accomplish this by the use of relays having their coils connected in the trunk lines between the selectors or other

switches, said relays in no way interfering with the use of the trunk lines for switching and telephonic purposes, and only coming into play for releasing purposes when the subscriber hangs up his telephone. The character and advantages of my invention will, however, hereinafter more fully appear.

In the accompanying drawings, Figure 1 is a diagram showing the circuits and apparatus comprised in one form of my invention. Figs. 2, 3, 4 and 5 shew other forms of my invention. Figs. 6 and 7 taken together show in a similar manner a calling and a called subscriber connected through the central office switching apparatus in connection with which I have elected to describe my invention, and in the said figures I show the form of my invention as it appears in Fig. 1. In Fig. 8 I show the form of my invention shown in Fig. 1 applied to each subscriber's line, as well as to each trunk line.

Figs. 8 and 7, it will be understood, represent the same condition represented by Figs. 6 and 7. In the said Figs. 6 and 7 there is shown the calling substation #5000, which has allotted to it the first-selector F of the type disclosed in United States Patent No. 815,321, granted March 13, 1906, to Keith, Erickson & Erickson. It will be seen that the central battery b has its positive terminal preferably grounded at g. The operating relays are normally connected to the non-grounded terminal of said battery, so that by grounding his line conductors the subscriber operates his switch, as is usually the custom in systems of this class. In addition to the said selector F, there is shown a second-selector G and a connector H, and another selector I, the latter allotted to the called line. The said connector may be of the general type disclosed in United States Patent No. 815,176, granted March 13, 1906, to Keith, Erickson & Erickson. At J there is shown a ringer generator and at K a busy signaling machine. The switch releasing device of my invention may be considered as an attachment which may be electrically connected with the central office switches in any suitable manner. In Fig. 8 a releasing device is used in connection with each subscriber's line, and there is also one for each trunk

line between the first-selectors and the second-selectors; while by the arrangement shown in Fig. 6 it will be seen that my releasing apparatus is used in such manner 5 that there is one for each trunk line only. Of course, it will be evident that in the first case—that is, in the case illustrated in Fig. 8—the number of releasing devices will be much larger than with the arrangement 10 shown in Figs. 6 and 7.

As diagrammatically shown in Fig. 1, my invention comprises two relays 2 and 3 which are double-wound. The windings 4 and 5 of the relay 2 are so arranged that 15 when current is passing through both windings simultaneously the said relay becomes operatively energized and attracts the armature 6, which latter is pivotally mounted at 7. The windings 8 and 9 of the relay 3 are 20 arranged differentially—that is, when both windings 8 and 9 carry current in the same direction the magnetizing influence of the current in one winding opposes that of the other, hence the relay does not operatively 25 energize. The windings 4 and 8 are connected in multiple; likewise the windings 5 and 9 are also connected in multiple. The operation of the device is as follows: When 30 the spring 10 is pressed onto the ground spring 11 an energizing circuit is established through the relays 2 and 3 as follows: from the battery 6 through the relay 12, switch 13, then the circuit divides, one branch passing through the winding 8 of 35 the relay 3, and the other through the winding 4 of the relay 2, then the branches meet and continue through the springs 10 and 11 to ground. The said relays 2 and 3 both 40 energize and exert an attractive force upon the common armature 6, tending to move the said armature toward each relay core; but the relay 3 exerts the greater influence, since the armature is normally in contact 45 with this relay core, while some little space separates the armature from the core of the relay 2. The attractive force of the relay 3, together with the force due to the tension of the spring 14, is sufficient to retain the armature 6 in normal position, as shown. 50 Similarly, when the spring 15 is pressed onto the ground spring 11 an energizing circuit is set up through the windings 5 and 9, with the same result as above stated. Now suppose that both springs 10 and 15 55 are pressed against the ground spring 11 simultaneously. The same energizing circuits are again established, but since the relay 3 is differentially wound and the magnetizing influence of the winding 8 opposes 60 the magnetizing influence of the winding 9, the relay 3 does not tend to retain the armature in normal position; and since both windings 4 and 5 now carry current, the relay 2 energizes sufficiently to overcome the 65 force of the spring 14, whereby the armature

6 is attracted toward the core of the relay 2, carrying the spring 14 into engagement with the spring 16 and thereby closing a circuit through the magnet 17. When the springs 15 and 10 return to normal position and break the energizing circuit through the relays 2 and 3, the armature 6, owing to the tension of the spring 14, returns to normal position. The relays 2 and 3 may be wound to any suitable resistance, 70 but with a battery of fifty volts good results are obtained when the windings 4, 5, 8 and 9 are wound to a resistance of twenty ohms each. 75

In the modification shown in Fig. 2 the relays 4 and 5 correspond to the windings 4 and 5, respectively, of the relay 2. The relay 3 does not have the windings 8 and 9 differentially arranged in this modification. When the spring 10 is pressed onto the ground spring 11 the windings 4 and 8, being in parallel, as above, carry current, and the relays 4 and 3 energize. The relay 4 attracts its armature 18 and the relay 3 exerts an attracting force upon the armature 6; but the latter is unable to respond, since it is locked in normal position by the armature 19. When the spring 15 is pressed onto the ground spring 11 the relay 5 and the winding 9 carry current, and the relays 4 and 5 energize. In this case the armature 19 is attracted, but the armature 6 is still locked in normal position by the armature 18. When both springs 10 and 15 are pressed simultaneously both relays 4 and 5 attract their respective armatures 18 and 19 simultaneously; then the armature 6 is permitted to respond to the attracting force of the relay 3, and moves about the pivot point 7, pressing the springs 14 and 16 into engagement, whereby the energizing circuit through the magnet 17 is closed. Upon the deenergization of the relays 4, 5 and 3 their respective armatures return to normal position, as shown. 95

In Fig. 3 is shown an arrangement of relays somewhat like that shown in Fig. 2. In this case, however, when the spring 10 is pressed the relay 4 and relay 3 energize and attract their respective armatures 18 and 6, whereby the armature 6 closes the springs 14 and 16 in contact; but the relays 4 and 5 are so arranged that the springs 20 and 21 engage only when both relays operate simultaneously, and the operation of either relay alone is without effect. The engagement of the springs 15 and 11 produces an energizing circuit through the relay 5 and winding 9 with the above noted result. Now when the springs 10 and 15 are pressed simultaneously both relays 4 and 5 energize simultaneously; also, the relay 3 operatively energizes, since the windings 8 and 9 are nondifferential. Since all three relays are operatively energized simultaneously, 110

ously the circuit through the magnet 17 is closed. When the springs 10, 11 and 15 again disengage, the relays return to their normal positions, as shown.

5 The device shown in Fig. 4 is essentially different mechanically from the arrangement shown in Fig. 1, but the relay windings and circuit connections are exactly the same. The relay 2 is like the relay 2 of Fig. 1, and the relay 3 is like the relay 3 of said Fig. 1 except that each winding 8 and 9 is wound on a separate core, as shown. The common armature 6 of Fig. 4 is pivoted at 7 and is secured to the core of the winding 8. When the spring 10 is grounded the current passes through the windings 4 and 8 in multiple. The attracting influence of the winding 8 is directed toward the core of the winding 9, but this core and winding 9 being stationary the attracting force draws the core and winding 8 toward the core of the winding 9, and this force, together with that of the spring 14, is sufficient to overcome the attractive force exerted by the relay 2 on the other end of the armature, and accordingly the armature remains in normal position. Likewise, when the spring 15 is pressed onto the ground spring 11 a similar result is brought about. Evidently, then, the force existing between the two cores of the windings 8 and 9 is one of attraction when each winding carries current alone; but when both springs 10 and 15 are grounded simultaneously, both windings 8 and 9 become operative simultaneously, but the force now existing between the two cores is one of repulsion, since the two windings 8 and 9, as explained, are differentially arranged, and the armature 6 moves about the pivot point 7, placing the springs 14 and 16 in contact. The relay 2, of course, becomes energized and assists the relay 3 and thereby renders the operation positive.

In Fig. 5 is shown the modification of Fig. 3, except that the relays 4 and 5 of Fig. 5 perform other functions in addition to closing an energizing circuit through the magnet 17. When the relay 4 energizes, as explained, the springs 22 and 23 engage, whereby a circuit is closed through the magnet 24. Similarly, when the relay 5 energizes, a circuit is closed through the magnet 25, and when both relays 4 and 5 operate simultaneously a circuit is closed through the magnet 17. The operation of the relays 3, 4 and 5 in this instance is like the operation of the same relays shown in Fig. 3.

My invention may be used for releasing in an automatic telephone system, and a clear understanding of the operations when used as a releasing device may be had from an explanation of its use in connection with the automatic telephone system illustrated in Figs. 6 and 7.

58 The substation may be of any suitable or approved type. Substation #5000, for in-

stance, is provided with a receiver 26, transmitter 27, ringer 28, induction-coil 29, switch-hook 30, impulse wheel 31, cam latch 32 for normally locking the dial, and a dog 33. The impulse wheel 31 is, of course, provided with a set of vertical impulse teeth 35 and a rotary impulse tooth 36 for operating, respectively, the vertical impulse spring 38 and the rotary impulse spring 37 with respect to the ground post 39. The substation ground G' is permanently connected to the ground spring 40, which latter is normally held away from the ground spring 41 by the insulating tip 42 upon the end of the cam-latch 32. Said insulating tip normally rests opposite the angled terminal of the ground spring 40, as shown at substation #2200. It will be understood, of course, that the subscriber's dial (not shown), the impulse wheel 31 and the cam dog 33 are all rigidly secured to the shaft 43. While the receiver is on the switch-hook the switch-hook-cam-arm 44 removes the ground spring 40 from the insulating tip 42, so that the cam-latch 32 falls in front of the pin 45 on the end of the cam dog 33, whereby it becomes impossible to rotate the dial. When the receiver is removed, however, the switch-hook is raised by a suitable spring (not shown), and the cam-arm 44 by engaging the face 46 of the cam-latch 32 raises the latter sufficiently to permit the pin 45 to pass under the cam-latch when the dial is rotated sufficiently. When the cam-arm 44 leaves its normal position, the ground spring 40 falls against the insulating tip 42 and remains there out of engagement with the other ground spring 41 until the dial is rotated, since the cam-arm 44 does not raise the cam-latch 32 sufficiently to permit the tip 42 to clear the angled section on the end of the ground spring 40. The extreme end of the cam-latch 32, which is engaged by the dog 33, is rounded off in such a manner that when the dial is rotated, the pin 45 slides beneath the said rounded section and raises the cam-latch 32 a trifle, so that the insulating tip 42 may now leave the ground spring 40, permitting the latter to engage the ground spring 41, and thus establishing connection between ground G' and the ground post 39. When the receiver is on the hook the cam 47 engages the spring 48 and thereby bridges the ringer 28 across the line. By engaging the spring 48 the said cam-arm 47 not only closes the substation ringing circuit, but also separates the springs 51 and 52 and opens the primary circuit; but when the switch-hook is up the primary circuit is closed. Furthermore, while the dial is being operated, and, therefore, while the cam 53 of the dog 33 is out of normal position, the primary circuit is opened at the point between the springs 51 and 52, so that no electric impulses which may be delivered to either of the subscriber's line conductors individually shall

883,881,1

58,59
5 pass through the transmitter to the other
6 side of the line. The switch-hook cam 54
7 is provided for controlling the release springs
8 55, 56 and 57, which release springs are
9 pressed into contact, grounding the sub-
10 subscriber's line conductors simultaneously when
11 it is desired to release the central office
12 switching apparatus. The signaling button
13 58 has the office of controlling the spring 59
14 that normally rests in engagement with the
15 contact point 60, but from which it is sepa-
rated and carried into engagement with the
ground contact 61 when the button 58 is
pressed, whereby only the vertical side of the
16 subscriber's line may be grounded when
17 signaling.

The first selector F, as shown in Fig. 6, is the terminal of the subscriber's vertical and rotary line conductors 62 and 63, which 20 conductors are normally connected with the vertical and rotary line relays 64 and 65 of said selector. The side switch wipers 66 and 67 are also connected with the line conductors 62 and 63, the wiper 66 being normally in engagement with the contact point 68, and the wiper 67 with the contact point 69. As is well known, the side switch comprises besides the side switch wipers 66 and 67 the private side switch wiper 70 and the 25 rotary magnet side switch wiper 71. The side switch is controlled by the private magnet 72, and in the normal or first position of the side switch the side switch wipers 66, 67, 70 and 71 engage the contact points 68, 69, 73 and 74, respectively. In the second 30 position of the side switch said wipers rest on the contact points 75, 76, 77 and 78, respectively; and in the third position they are in engagement with the contact points 79, 80, 81 and 82, respectively. Through 35

361 the medium of the vertical line relay 64, and while the side switch is in first position, the subscriber controls the vertical magnet 83, which latter operates the switch-shaft (not shown) vertically, which shaft carries the line wipers 84 and 85 and the private wiper 86. Through the medium of the rotary line relay 65 the subscriber controls the private magnet 72 and, therefore, the side switch. 011

45 50 When the side switch is in second position

the rotary magnet 87 is energized and the switch-shaft that carries the wipers 84, 85 and 86 is operated in a rotary direction. The vertical and rotary line relays 64 and 65 together provide the means by which the release magnet 88 is controlled by the subscriber. The switch-shaft of the selector F carries a so-called normal post arm 89 which, when the shaft is in an off-normal position, permits the spring 90 to engage the contact point 91 and thereby make a ground connection with the private normal conductor. The private normal conductor leads to the connector private bunk, and by way of said private normal conductor the

bridge-cut-off relay 93 is energized whenever any subscriber calls the substation #5000. Said relay 93 is provided to control the connection between the vertical and rotary line relays 64 and 65 and the battery *b*. It is customary to thus disconnect said relays from the battery and from across the line whenever the line allotted to the selector is called, for well-known reasons. Said connection is controlled by the bridge-cut-off relay 93 through the medium of the springs which it controls. 70 75

The second-selector G is the same as the first-selector switch with the exception that there are no normal conductors, such as the 80 normal conductors 95 and 96 of the selector-switch F. There is also no use in the second-selector for a bridge-cut-off relay, such as the relay 93 of the selector F, and it is also omitted, and the line relays are connected directly to the battery lead. The private normal conductor 94 of the selector F is of no use in connection with the second-selector, and is also omitted. Since like parts are likewise represented throughout the drawings, the vertical magnet 97, the rotary magnet 98, the release magnet 99, and the private magnet 100 will be recognized and understood. The said private magnet 100, of course, controls the side switch wipers 101, 102, 103 and 104, the said private magnet also controlling the circuit of the release magnet 99 and of the vertical magnet 97 in the usual manner by means of the springs 106, 107 and 108. The vertical movement of the switch-shaft, and, therefore, of the wipers 109, 110 and 111, is controlled by the vertical magnet 97 and the rotary movement by the rotary magnet 98, the said rotary magnet circuit being provided with the usual interrupter springs 112. The operative magnets of the switch are, of course, controlled by the subscriber through the use of the vertical and rotary line relays 113 and 114, as is well known. Said relays have under their control the usual springs 115, 116 and 117.

The connector-switch H (Fig. 7) is of a well-known form. The mechanical details of the selector and connector, as is well known, are very much the same, although there is some material difference in the circuits. The connector switch-shaft, like the shaft of the selectors, (and which is not shown), carries the usual line wipers 118 and 119 and the private wiper 120. The connector switch is also controlled by the calling subscriber through the medium of the vertical and rotary line relays 121 and 122. The vertical line relay 121 directly controls the vertical magnet 123 and also the rotary magnet 124. The office of the said vertical magnet 123 is to give the shaft and the shaft wipers their vertical movement, and the rotary magnet 124 imparts to the said shaft 130

a rotary or circular motion. The rotary line relay 122 controls the private magnet 125, which latter, under certain conditions, in turn controls the vertical and rotary magnets 123 and 124 and the release magnet 126, and also the side switch wipers 127, 128, 129 and 130, all of which are shown. The said side switch, like the side switch of the first selector, has a normal or first position, a second position and a third position. In normal position the respective side switch wipers engage the contact points 131, 132, 133 and 134; in second position they engage the contact points 135, 136, 137 and 138, and in third position the contact points 139, 140, 141 and 142. The connector divides the circuit that passes through it into two sections by the use of the condensers 145 and 146. The connector has, in addition, a ringer relay 147 by means of which the ringer generator *J* is bridged across the terminals of the called line to signal the called subscriber. The said connector also has a differential relay 154 provided with the windings 155 and 156. The winding 155 is in series with the vertical line relay 121, and the winding 156 is in series with the rotary line relay 122. There is also a back-bridge relay 157 allotted to the connector, said relay having the windings 158 and 159, which windings, when the side switch is in third position, are bridged across the main talking circuit on the called subscriber's side of the condensers 145 and 146, and in series with the central battery, for providing the called subscriber with talking battery current when he answers. Said relay 157 is adapted to energize when the said called subscriber answers, and it in turn bridges the battery across the main talking circuit on the calling subscriber's side of the condensers 145 and 146, and between the windings 155 and 156 of the differential relay 154.

To call the number 2200 the subscriber at substation #5000 operates the dial in the well-known manner for the first digit 2, whereby the vertical line conductor 62 becomes grounded twice and the rotary line conductor 63 once, as a result operating the vertical and rotary line relays 64 and 65, which latter in turn close energizing circuits, in the well-known manner, through the vertical and rotary magnets 83 and 87, respectively, which, upon operating, carry the shaft wipers 84 and 85 to a trunk line leading to the selector *G*. Grounding the line conductors 62 and 63 for the second digit has the effect of energizing the vertical and rotary line relays 113 and 114 of the selector *G*. This energizing current flows through the windings 4 and 8 of the releasing device *A* over one side, and through the winding 5 of said device over the other side of the main line (Fig. 6). Upon receiving current the said windings energize the relays 2 and 3,

which relays operate as previously explained. The second-selector *G*, upon receiving the vertical and rotary impulses, operates in the usual manner to carry the shaft wipers 109 and 110 into engagement with a trunk line leading to the connector-switch *H*. The result of operating the dial for the last two digits is to ground the line conductors 62 and 63 again and to energize the connector vertical and rotary line relays 121 and 122. 70

The energizing circuit for the vertical line relay 121 comprises the windings 4 and 8 of the releasing devices *A* and *A'* and the winding 155 of the differential relay 154; and the energizing circuit for the rotary line relay 122 comprises the windings 5 and 9 of said releasing devices and the winding 156 of the differential relay 154. The effect on the releasing devices *A* and *A'* is already known. The differential relay energizes 85 each time that either of the vertical or rotary line relays 121 or 122 energize, but it is of no consequence at this point. The connector vertical line relay 121 upon energizing ten times operates the vertical magnet 90 123 ten times, whereby the shaft wipers are carried to the tenth level of the connector bank. The rotary line relay upon energizing ten times operates to energize the rotary magnet 124 ten times, whereby the wipers 95 are carried into engagement with the desired line. After the connector side switch passes to third position the calling subscriber, by pressing his signaling button 58 and grounding the vertical line conductor 100 62, energizes the vertical line relay 121 of the connector, which in turn operates to energize the ringer relay 147, since the side switch wiper 129 is in third position in engagement with the contact point 141. The 105 ringer relay then operates to connect the ringer generator *J* across the terminals of the called subscriber's line as long as the calling subscriber continues to press his signaling button, whereby the bell of the 110 desired substation is rung. It will be noticed that the winding 158 of the back-bridge relay 157 is connected to the vertical side of the main line, and that the other terminal of said winding is connected through the differential relay springs 160 and 161 with the non-grounded terminal of central battery *b*. It will also be noticed that the winding 159 has one terminal permanently connected to the rotary side of the main line, while the 115 other terminal is connected to the side switch wiper 130. The said side switch wiper 130, when in third position, engages the grounded contact point 142, so that when the called subscriber removes his receiver 120 and bridges his transmitter across the line, the back-bridge relay 157 energizes and the back-bridge relay spring 162 is shifted from the central battery *b* to the ground connection to the 125 ground side of the spring 164 so as to break the call 130.

ing subscriber is provided with talking current. Since, by the said operation of the relay 157, the battery *b* is connected in series with the windings 155 and 156 of the differential relay 154, and through said windings and the windings of the vertical and rotary line relays 121 and 122 said battery is bridged across the calling subscriber's side of the main line. The calling subscriber is, of course, then provided with talking battery current that flows over the following circuit: from ground G' to the contact point 142, side switch wiper 130, back-bridge relay springs 164 and 162 to the winding 156 of the differential relay 154, rotary line relay 122, through the windings 9 and 5 of the releasing device A' , and through the windings 9 and 5 of the releasing device A to the rotary line conductor 63, thence through the transmitter 27 of the substation #5000 to the vertical line conductor 62, through the windings 4 and 8 of the releasing device A and 4 and 8 of the releasing device A' to the vertical line relay 121 of the connector, thence through the winding 155 of the differential relay 154 to the non-grounded terminal of battery *b*. As already explained, the releasing devices A and A' will not operate to shift their armatures 6 when battery current is flowing in the direction described. Also, the differential relay 154 at the connector will not energize when the current is flowing in the circuit as described. However, when the calling subscriber hangs up his receiver after the called subscriber answers, he grounds the vertical and rotary line conductors 62 and 63 simultaneously by pressing the release springs 55, 56 and 57 into contact, and as a result the windings 5 and 9 of the releasing devices A and A' are totally or partially short-circuited through ground G' at the substation and ground G' at the connector. As a result the said releasing devices become unbalanced, as well as the differential relay 154 of the connector. As soon as the differential relay 154 of the connector energizes, the energizing circuit for the back-bridge relay 157 is then destroyed, which relay upon deenergizing restores the spring 162 to the non-grounded spring 163. As a result the rotary line relay 122, which deenergizes at the same time that the relay 154 is unbalanced, reenergizes; and since the vertical line relay 121 is still energized the line relay release springs 165 and 166 come into contact, energizing the release magnet 126 and producing the release of the connector. The windings 8 and 9 of the releasing devices A and A' being neutralized by the current that energizes the line relays 121 and 122 of the connector—the windings 4 and 5 reinforcing each other—the armature 6 is attracted and the springs 14 and 16 are carried into contact; and in the case of the

releasing device A' the back-release relay 149 of the selector G is energized, thus energizing the release magnet 99, and in the case of the releasing device A the back-release relay 151 is energized, whereby the release magnet 88 is energized.

Now as soon as the substation release springs separate, the release circuits are all destroyed and the switches fully restored. Of course, if connection is not established with the desired line—for example, as when the called subscriber is busy—, then when the calling subscriber hangs up his receiver he grounds both the vertical and rotary line conductors simultaneously; but since the connector back-bridge relay is not energized the line relays 121 and 122 energize at the same time over circuits that are already known, and at the same time the releasing devices A and A' are unbalanced, as already explained, with the result that as soon as the substation release springs separate, all the switches are fully restored. The connector, of course, releases at once.

When my releasing device is used as shown in Fig. 8 the selector-switch L is somewhat different from the selector F and the selector M and the corresponding switch G (Fig. 6) are also different. In each case the difference between the corresponding switches is found in the absence of the release relays, such as the release relay 151 of the selector F , and the spring on the private magnet at which one terminal of the release magnet terminates. Said release magnet terminal is instead connected to the spring 14 of the releasing device A , as shown in said Fig. 8. Otherwise the switches are identical, and like parts being similarly represented, the various parts will be readily recognized upon referring to the drawings. Of course, it will be understood that the operation of the switches when Figs. 8 and 7 are considered together is the same as when Figs. 6 and 7 are considered together, the only difference being that when the release occurs the armatures 6 directly energize the release magnets 152 and 153 of the switches M and L , instead of through the medium of a release relay. In the different drawings different batteries are shown, but the system will operate successfully with only one battery.

From the foregoing it will be seen that I provide automatic means for cutting off or opening up the bridges of the selectors, and that I also provide means for releasing the said selectors without using third conductors in the trunk lines. The relays in the talking circuit do not interfere with the switching or telephoning operations and are effective in releasing the selectors when the subscribers are through talking. I thus get rid of the bridges on the talking circuit without increasing the amount of copper or

other material necessary for the trunk lines between the switches. As shown in Fig. 6, the private wipers of the selectors are included in the energizing circuits of the release relays of the selectors. As shown in Fig. 8, however, no release relays are employed for the selectors, and the private wipers are not included in any release circuits, the release magnets of the selectors having local circuits which are closed or controlled directly by the special relays, the coils of which are in the main line circuit. As illustrated, however, my invention may be employed in various ways, and may be changed or modified more or less without departing from the spirit thereof. For this reason, and for the broader purposes of my invention, I do not limit myself to any particular form or construction. So far as I am now aware, I am the first to cut off the selector bridges, so as to leave only the connector bridge or bridges across the talking circuit during conversation, and to then release the selectors without the use of third conductors in the trunk lines. More specifically considered, the preferred embodiment of my invention is shown in Fig. 6. As shown, the system to which my invention is applied is operated on the common battery principle, current for charging the subscribers' transmitters being derived from means located at the exchange or central station. Obviously, however, the talking current may be otherwise supplied, in accordance with any suitable or known practice without departing from the scope or broader aspect of my invention.

It will be seen that the coils 8 and 9 and the core 3 constitute electromagnetic means for preventing a premature release or disconnection between subscribers. By this I mean that the said coils and core serve as an electromagnetic locking device for preventing accidental release or disconnection before the same is desired.

As a guarding potential is established for each subscriber's line, it is clear that means are provided for electrically repelling interference with a busy subscriber. As guarding potentials are provided for the trunks, it is also true that means are provided for electrically repelling interference with a busy trunk.

What I claim as my invention is:—

1. In a telephone exchange system, the combination of a talking circuit divided into sections, selectors for connecting said sections, a relay bridge in each of said selectors bridged across the corresponding section of said talking circuit, auxiliary electric means associated with each selector controlled by its relay bridge, means for cutting off said bridges during use of said circuit for talking, common battery means for supplying talking current to said

circuit, and means including relay coils in the talking circuit for releasing said selectors to normal condition.

2. In a telephone exchange system, the combination of a talking circuit, an automatic switch for connecting one section of the circuit with another, a relay bridge in the switch across the corresponding section of the talking circuit, auxiliary electric means associated with the switch controlled by the relay bridge, means for cutting off said bridge during use of said circuit for talking, common battery means for supplying talking current to said circuit, and means including a relay coil in the talking circuit for releasing and restoring said automatic switch to normal condition.

3. In a telephone exchange system, the combination of a talking circuit, a plurality of relay bridges across the conductors of said circuit, auxiliary circuits associated with each bridge and controlled thereby, means for cutting off said bridges during use of said circuit for talking, common battery means for supplying talking current to said circuit, and means including relay coils in the talking circuit for reestablishing said bridges on said circuit.

4. In a telephone exchange system, the combination of a talking circuit, a selector for connecting one section of the circuit with another, a relay bridge in the selector across the corresponding section of the talking circuit, auxiliary electric means controlled by said bridge, means for cutting off or opening up the bridge during use of the circuit for talking, release mechanism for said selector, common battery means for supplying talking current to said circuit, and means including one or more relay coils in the talking circuit for controlling said mechanism to release the selector.

5. In a telephone exchange system, the combination of an automatic switch, a line circuit thereto, release mechanism for said switch, a relay bridge across said line circuit controlling said release mechanism, automatic means for cutting off or opening up said bridge during use of the circuit for talking, a relay for controlling said mechanism, common battery means for supplying talking current to said circuit, and an energizing circuit for said relay including the conductors of the line circuit, said relay having a winding included serially in the line circuit.

6. In a telephone exchange system, the combination of a line circuit extending between calling and called subscribers' stations, automatic switches having relay bridges on said circuit, auxiliary apparatus controlled by each bridge and associated therewith, automatic means for cutting off said bridges during use of the circuit for talking, common battery means for supplying talking current to said

- means for supplying talking current, and means including relays for releasing the automatic switches, said relays having windings included in the line circuit.
- 5 7. In a telephone exchange system, the combination of a line circuit between calling and called subscribers, relay bridges on said circuit, auxiliary apparatus controlled by each bridge and associated therewith, automatic means for cutting off said bridges during talking, and means including differential relay windings included in said circuit for reestablishing the bridges on said circuit.
- 10 8. In a telephone exchange system, a line circuit, a trunk line in said circuit, a relay bridge on said circuit, auxiliary apparatus controlled by said bridge and associated therewith, automatic means for cutting off or opening up said bridge during talking, and means including a pair of differential relay coils included in said trunk line for reestablishing the bridge on the circuit.
- 15 9. In a telephone exchange system, calling and called lines, a trunk line connecting the two, a relay bridge across said trunk line, auxiliary circuits associated with said bridge and controlled thereby, automatic means for cutting off or opening up said bridge during talking, common battery connections for supplying talking current to the lines, and means including relay coils in the trunk connection for restoring said bridge to normal condition.
- 20 35 10. In a telephone exchange system, a talking circuit, a connector and a selector in said circuit, a relay bridge across the conductors of said circuit, auxiliary electric apparatus controlled by said bridge, means for cutting off said bridge during talking, means for releasing the connector, common battery connections for supplying talking current to the lines, and means including relay coils for releasing the selector and re-establishing said bridge, each relay coil having both terminals thereof connected with said talking circuit.
- 25 11. In a telephone exchange system, a talking circuit, a bridge across the conductors of said circuit, automatic means for cutting off or opening up said bridge during talking, relay coils in said bridge, operating means having local circuits controlled by said coils, common battery connections for supplying talking current to the lines, and means including relay coils in the talking circuit for reestablishing said first-mentioned relays in bridge on the circuit.
- 30 12. In a telephone exchange system, the combination of a talking circuit, selectors having relay bridges across the conductors of said circuit, auxiliary apparatus controlled by each bridge and associated therewith, means for cutting off said bridges during use of said circuit for talking, means including relay coils in the talking circuit for releasing and restoring said selectors to normal condition, and electro-magnetic locking means for preventing a premature release or disconnection between subscribers.
- 35 13. In a telephone exchange system, the combination of a talking circuit, an automatic switch having a relay bridge across the conductors of said circuit, auxiliary apparatus controlled by said bridge and associated therewith, means for cutting off said bridge during use of said circuit for talking, means including a relay coil in the talking circuit for releasing and restoring said automatic switch to normal condition, and electromagnetic locking means for preventing a premature release or disconnection between subscribers.
- 40 14. In a telephone exchange system the combination of a talking circuit, a plurality of relay bridges across the conductors of said circuit, auxiliary apparatus controlled by each bridge and associated therewith, means for cutting off said bridges during use of said circuit for talking, means including relay coils in the talking circuit for releasing and reestablishing said bridges on said circuit, and electromagnetic locking means for preventing a premature release or disconnection between subscribers.
- 45 15. In a telephone exchange system, the combination of a talking circuit, a selector in said circuit, provided with a relay bridge across the conductors of said circuit, auxiliary apparatus controlled by said bridge and associated therewith, means for cutting off or opening up the bridge during use of the circuit for talking, release mechanism for said selector, means including one or more relay coils in the talking circuit for controlling said mechanism to release the selector, and electromagnetic locking means for preventing a premature release or disconnection between subscribers.
- 50 16. In a telephone exchange system, the combination of an automatic switch having a line circuit release mechanism for said switch, a relay bridge on said circuit, auxiliary apparatus controlled by said bridge and associated therewith, automatic means for cutting off or opening up said bridge during use of the circuit for talking, a relay for controlling said mechanism, an energizing circuit for said relay including the conductors of the line circuit, said relay having a winding included serially in the line circuit, and electromagnetic locking means for preventing a premature release or disconnection between subscribers.
- 55 17. In a telephone exchange system, the combination of a line circuit extending between calling and called subscribers' stations, automatic switches having relay bridges across the conductors of said circuit, auxiliary apparatus controlled by each

- bridge and associated therewith, automatic means for cutting off or opening up said bridges during use of the circuit for talking, means including relays for releasing the 5 automatic switches, said relays having windings included in the line circuit and electromagnetic locking means for preventing a premature release or disconnection between subscribers.
- 10 18. In a telephone exchange system, the combination of a line circuit between calling and called subscribers, relay bridges across the conductors of said circuit, auxiliary apparatus controlled by each bridge 15 and associated therewith, automatic means for cutting off said bridges during talking, means including differential relay windings included in said circuit for releasing and re-establishing the bridges on said circuit, and 20 electromagnetic locking means for preventing a premature release or disconnection between subscribers.
19. In a telephone exchange system, a line circuit, a trunk line in said circuit, a relay bridge on said circuit, auxiliary apparatus controlled by said bridge and associated therewith, automatic means for cutting off or opening up said bridge during talking, means including a pair of differential relay coils included in said trunk line 25 for releasing and re-establishing the bridge on the circuit, and electromagnetic locking means for preventing a premature release or disconnection between subscribers.
- 30 20. In a telephone exchange system calling and called telephone lines, a trunk line connection between said telephone lines, a relay bridge across the conductors of said trunk line connection, auxiliary apparatus 35 controlled by said bridge and associated therewith, automatic means for cutting off or opening up said bridge during talking, means including relay coils in the trunk connection for releasing and restoring said bridge to normal condition, and electromagnetic locking means for preventing a premature release or disconnection between subscribers.
- 40 21. In a telephone exchange system, a talking circuit, a connector and a selector in said circuit, a relay bridge on the circuit auxiliary apparatus controlled by said bridge and associated therewith, means for cutting off or opening up said bridge during talking, means for releasing the connector, means including relay coils for releasing the selector and re-establishing said bridge, each relay coil having both terminals thereof connected with said talking circuit, and electromagnetic locking means for preventing a premature release or disconnection between subscribers.
- 45 22. In a telephone exchange system, a talking circuit, a bridge across the conductors of said circuit, automatic means for cutting off or opening up said bridge during talking, relay coils in said bridge auxiliary apparatus controlled thereby, means including relay coils in the talking circuit for releasing and re-establishing said first-mentioned relays in bridge on the circuit, and electromagnetic locking means for preventing a premature release or disconnection between subscribers.
- 50 23. In a telephone exchange system, the combination of a talking circuit, selectors each having relay bridges across the conductors of said circuit, means in each selector having one motion controlled in one manner and another motion controlled in a different manner for connecting one section of the talking circuit with another, the said means in each switch controlled by its relay bridge, means for cutting off said bridges during use of said circuit for talking, means including relay coils in the talking circuit for releasing and restoring said selectors to normal condition, a central source of talking current, and means operated from the same source for electrically 55 repelling interference with a busy subscriber.
- 55 24. In a telephone exchange system, the combination of a talking circuit, an automatic switch having a relay bridge across the conductors of said circuit, means in said switch having one motion controlled in one manner and another motion controlled in a different manner for connecting one section of the talking circuit with another, said means controlled by said relay bridge, means for cutting off said bridge during use of said circuit for talking, means including a relay coil in the talking circuit for releasing and restoring said automatic switch to 60 normal condition, a central source of talking current, and means operated from the same source for electrically repelling interference with a busy subscriber.
- 65 25. In a telephone exchange system, the combination of a talking circuit, a plurality of relay bridges across the conductors of said circuit, means associated with each bridge having one motion controlled in one manner and another motion controlled in a 70 different manner for connecting one section of the talking circuit with another and controlled by its relay bridge, means for cutting off said bridges during use of said circuit for talking, means including relay coils 75 in the talking circuit for re-establishing said bridges on said circuit, a central source of talking current, and means operated from the same source for electrically repelling interference with a busy subscriber.
- 80 26. In a telephone exchange system, the combination of a talking circuit, a selector having a relay bridge across the conductors of said circuit, means in said selector having one motion controlled in one manner 85

- and another motion controlled in a different manner for connecting one section of the talking circuit with another, said means controlled by said relay bridge, means for cutting off or opening up the bridge during use of the circuit for talking, release mechanism for said selector, means including one or more relay coils in the talking circuit for controlling said mechanism to release the selector, a central source of talking current, and means operated from the same source for electrically repelling interference with a busy subscriber.
27. In a telephone exchange system, the combination of an automatic switch having a line circuit, release mechanism for said switch, a relay bridge on said circuit, auxiliary apparatus controlled by said bridge and associated therewith, automatic means for cutting off or opening up said bridge during use of the circuit for talking, a relay for controlling said mechanism, an energizing circuit for said relay including the conductors of the line circuit, said relay having a winding included serially in the line circuit, a central source of talking current, and means operated from the same source for electrically repelling interference with a busy subscriber.
28. In a telephone exchange system, the combination of a line circuit connecting two subscribers, automatic switches each having a relay bridge across the conductors of the circuit, means in each automatic switch having one motion controlled in one manner and another motion controlled in a different manner for connecting one section of the talking circuit with another, the said means in each switch controlled by its relay bridge, means for cutting off or opening up said bridges during use of the circuit for talking, means including relays for releasing the automatic switches, said relays having windings included in the line circuit, a central source of talking current, and means operated from the same source for electrically repelling interference with a busy subscriber.
29. In a telephone exchange system, the combination of a line circuit between calling and called subscribers, relay bridges across the conductors of said circuit, auxiliary apparatus controlled by each bridge and associated therewith, automatic means for cutting off said bridges during talking, means including differential relay windings included in said circuit for reestablishing the bridges on said circuit, a central source of talking current, and means operated from the same source for electrically repelling interference with a busy subscriber.
30. In a telephone exchange system, a line circuit, a trunk line in said circuit, a relay bridge on said circuit, auxiliary apparatus controlled by said bridge and associated therewith, automatic means for cutting off or opening up said bridge during talking, means including a pair of differential relay coils included in said trunk line for reestablishing the bridge on the circuit, a central source of talking current, and means operated from the same source for electrically repelling interference with a busy subscriber.
31. In a telephone exchange system, calling and called telephone lines, a trunk line connecting between said telephone lines, a relay bridge across the conductors of said trunk line connection, auxiliary apparatus controlled by said bridge and associated therewith, automatic means for cutting off or opening up said bridge during talking, means including relay coils in the trunk connection for restoring said bridge to normal condition, a central source of talking current, and means operated from the same source for electrically repelling interference with a busy subscriber.
32. In a telephone exchange system, a talking circuit, a connector and a selector in said circuit, a relay bridge across the conductors of the circuit, auxiliary apparatus controlled by said bridge and associated therewith, means for cutting off or opening up said bridge during talking, means for releasing the connector, means including relay coils for releasing the selector and reestablishing said bridge, each relay coil having both terminals thereof connected with said talking circuit, a central source of talking current, and means operated from the same source for electrically repelling interference with a busy subscriber.
33. In a telephone exchange system, a talking circuit, a bridge across the conductors of said circuit, automatic means for cutting off or opening up said bridge during talking, relay coils in said bridge, auxiliary apparatus controlled thereby, means including relay coils in the talking circuit for reestablishing said first-mentioned relays in bridge on the circuit, a central source of talking current, and means operated from the same source for electrically repelling interference with a busy subscriber.
34. In a telephone system, an automatic trunk selector having line wipers, a third wiper, a release relay, local energizing circuits for said relay including said third wiper, a busy test circuit including said third wiper, trunks adapted to be seized by said line wipers, each trunk having a contact adapted thereto and adapted to be seized by the said third wiper to include the same in said local circuits, automatic switches at the other ends of said trunks, means by which a calling subscriber transmits switch-operating impulses directly to the switch of any trunk seized by said selector, and common battery means for supplying talking cur-

rent to the calling line without causing a release of said selector.

35. In a telephone system, an automatic trunk selector having line wipers, a third wiper, a release relay, local energizing circuits for said relay including said third wiper, a busy test circuit including said wipers, trunks adapted to be seized by said line wipers and provided with relays for controlling said local circuits, automatic switches at the other ends of said trunks, means by which a calling subscriber transmits switch-operating impulses directly to the switch of any trunk seized by said selector, and common battery means for supplying talking current to the calling line without causing a release of said selector.

36. In a common battery telephone system, a trunk selector, conductively-continuous trunks leading from said selector, a release relay for the selector end of each trunk, selecting means in the selector responsive to the seize of any seized trunk, means by which original calling impulses are transmitted through the selector and over any selected trunk, and common battery means for supplying talking current.

37. In a common battery telephone system, an automatic trunk selector, local release circuits for said selector, trunks each provided with a relay for controlling one of said local circuits, and means by which original calling impulses are transmitted through the selector and over any selected trunk.

38. In a telephone system, common battery means for supplying talking current, a metallic trunk line, and a release magnet having a winding thereof included in one side of said metallic trunk line circuit included between calling and called subscribers.

39. In an automatic telephone system, a subscriber's line, a metallic circuit trunk line, a selector serving to connect said subscriber's line with said trunk line, controlling magnets for said selector, switches operated by said controlling magnets to open the circuit of said magnets upon the completion of a selection, electrocoupler mechanism included in the talking connection and bridged over the line circuit to actuate said selector to disconnect said subscriber's line from said trunk line, a called line, means for completing connection to the called line, and common battery connections for supplying talking current to the called line.

40. In an automatic telephone system, a subscriber's line, a selecting switch therefor, a trunk line, controlling magnets normally bridged across the subscriber's line for causing said switch to select and connect with said trunk line, means for automatically disconnecting said controlling magnets from

said line after their operation, a source of current adapted to supply current over said trunk line to said subscriber's line, means included in the talking connection and operated by current from said source over said trunk line to cause said switch to disconnect said subscriber's line from said trunk line, a called line, means for completing connection to the called line, and common battery connections for supplying talking current to the called line.

41. In an automatic telephone system, a metallic circuit line, a substation in said line, a selecting switch for said line, controlling magnets for said switch, a disconnect magnet for said switch, a metallic circuit trunk line, means at said substation for causing the selecting switch of said line to select and connect with said trunk line, means for automatically disconnecting said controlling magnets from said line after such selection and connection, means included in the talking connection and operated over the limbs of said trunk line for closing the circuit of said disconnect magnet to cause said selecting switch to release said trunk, a called line, means for completing connection to the called line, and common battery connections for supplying talking current to the called line.

42. In an automatic telephone system, a metallic circuit line, a substation and a selecting switch for said line, controlling magnets for said switch normally in operative relation with said line, a metallic circuit trunk line, means at said substation for causing its selecting switch to select and connect with said trunk line, means for automatically placing said controlling magnets in inoperative relation with said line after such selection and connection, relays connected with the limbs of said trunk and included in the talking connection, means controlled by said relays for causing said selecting switch to disconnect said line from said trunk line, a called line, means for completing connection to the called line, and common battery connections for supplying talking current to the called line.

43. In an automatic telephone system, a metallic circuit line, a third conductor, a substation and a selecting switch for said line, a pair of controlling magnets for said switch normally bridged across said line, a source of current connected between said magnets and a third conductor, a metallic circuit trunk line, means at said substation for connecting the limbs of said line with said third conductor for causing said selecting switch to select and connect with said trunk line, means for automatically disconnecting said controlling magnets from said line after such selection and connection, relays connected in the limbs of said trunk line, means controlled by said relays for

- causing said selecting switch to disconnect said line from said trunk line, a called line, means for completing connection to the called line, and common battery connections for supplying talking current to the called line.
44. In an automatic telephone system, a subscriber's line, a metallic circuit trunk line, a selector serving to connect said subscriber's line with said trunk line, controlling magnets for said selector, switches operated by said controlling magnets to open the circuit of said magnets upon the completion of a selection electromagnet mechanism included in the talking connection and controlled over the line circuit to actuate said selector to disconnect said subscriber's line from said trunk line, and a battery circuit which is closed during conversation and which includes the two sides of said trunk line in series.
45. In an automatic telephone system, a subscriber's line, a selecting switch therefor, a trunk line, controlling magnets normally bridged across the subscriber's line for causing said switch to select and connect with said trunk line, means for automatically disconnecting said controlling magnets from said line after their operation, a source of current adapted to supply current over said trunk line to said subscriber's line, means included in the talking connection and operated by current from said source over said trunk line to cause said switch to disconnect said subscriber's line from said trunk line, and a battery circuit which is closed during conversation and which includes the two sides of said trunk line in series.
46. In an automatic telephone system, a metallic circuit line, a substation in said line, a selecting switch for said line, controlling magnets for said switch, a disconnect magnet for said switch, a metallic circuit trunk line, means at said substation for causing the selecting switch of said line to select and connect with said trunk line, means for automatically disconnecting said controlling magnets from said line after such selection and connection, means included in the talking connection and operated over the limbs of said trunk line for closing the circuit of said disconnect magnet to cause said selecting switch to release said trunk, and common battery connections for supplying talking current to the calling line without releasing the connection with said trunk line.
47. In an automatic telephone system, a metallic circuit line, a substation and a selecting switch for said line, controlling magnets for said switch normally in operative relation with said line, a metallic circuit trunk line, means at said substation for causing its selecting switch to select and connect with said trunk line, means for automatically placing said controlling magnets in inoperative relation with said line after such selection and connection, relays connected with the limbs of said trunk and included in the talking connection, means controlled by said relays for causing said selecting switch to disconnect said line from said trunk line, and common battery connections for supplying talking current to the calling line without releasing the connection with said trunk line.
48. In an automatic telephone system, a subscriber's line, a metallic circuit trunk line, a selector serving to connect said subscriber's line with said trunk line, controlling magnets for said selector, switches operated by said controlling magnets to open the circuit of said magnets upon the completion of a selection electromagnet mechanism included in the talking connection and controlled over the line circuit to actuate said selector to disconnect said subscriber's line from said trunk line, and a battery circuit which is closed during conversation and which includes the two sides of said trunk line in series.
49. In an automatic telephone system, a metallic circuit line, a substation in said line, a selecting switch for said line, controlling magnets for said switch, a disconnect magnet for said switch, a metallic circuit trunk line, means at said substation for causing the selecting switch of said line to select and connect with said trunk line, means for automatically disconnecting said controlling magnets from said line after such selection and connection, means included in the talking connection and operated over the limbs of said trunk line for closing the circuit of said disconnect magnet to cause said selecting switch to release said trunk, and a battery circuit which is closed during conversation and which includes the two sides of said trunk line in series.
50. In an automatic telephone system, a metallic circuit line, a substation and a selecting switch for said line, controlling magnets for said switch normally in operative relation with said line, a metallic circuit trunk line, means at said substation for causing its selecting switch to select and connect with said trunk line, means for automatically placing said controlling magnets in inoperative relation with said line after such selection and connection, relays connected with the limbs of said trunk and included in the talking connection, means controlled by said relays for causing said selecting switch to disconnect said line from said trunk line, and a battery circuit which is closed during conversation and which includes the two sides of said trunk line in series.

51. In an automatic telephone system, a metallic circuit line, a third conductor, a substation and a selecting switch for said line, a pair of controlling magnets for said switch normally bridged across said line, a source of current connected between said magnets and a third conductor, a metallic circuit trunk line, means at said substation for connecting the limbs of said line with 5 said third conductor for causing said selecting switch to select and connect with said trunk line, means for automatically disconnecting said controlling magnets from said line after such selection and connection, relays connected in the limbs of said trunk line, means controlled by said relays for causing said selecting switch to disconnect said line from said trunk line, and a battery circuit which is closed during conversation 10 and which includes the two sides of said trunk line in series.
52. In a telephone system, an automatic selecting switch provided with a controlling relay which is normally in bridge of the 15 talking circuit of said switch, means for automatically opening up or cutting off said bridge, a central source of current for talking purposes, and means controlled over the talking circuit for releasing said switch, said 20 releasing means including a relay having
- both terminals thereof connected with the talking circuit.
53. In a telephone system, a line circuit, an automatic switch adapted to be controlled over said circuit, line relays for said switch, 35 means for automatically disconnecting the line relays of said switch from the circuit after the operation thereof, a central source of current for talking purposes, and means controlled over the line circuit for releasing 40 said switch, said releasing means including a relay provided with a winding which is connected in series in one side of the line circuit.
54. In a telephone system, a plurality of 45 step-by-step movable switches, a common battery talking circuit extending between said switches provided with means for releasing without using more than two conductors between switches, said switches having motion in one plane to select groups and motion in another plane to find a line in the selected group.

Signed by me at Chicago, Cook county, Illinois, this 16th day of January, 1907.

JHN ERICKSON.
